Primary Examiner — Antoine Duval Davis(74) *Attorney, Agent, or Firm* — Foley Hoag LLP; Rajesh Vallabh(57) **CLAIM**

The ornamental design for a sensing and tracking device, as shown and described.

DESCRIPTION

FIG. 1 is a perspective view of a sensing and tracking device showing our new design;

FIG. 2 is a bottom view thereof;

FIG. 3 is a front view thereof;

FIG. 4 is a top view thereof;

FIG. 5 is a right side view thereof;

FIG. 6 left side view thereof; and,

FIG. 7 is a rear view thereof.

The broken lines shown are included for the purpose of illustrating the unclaimed portions of the sensing and tracking device and form no part of the claimed design.

1 Claim, 3 Drawing Sheets(56)
